US00D662100S

(12) **United States Design Patent**
Van Den Nieuwenhuizen et al.

(10) **Patent No.:** US D662,100 S
(45) **Date of Patent:** ** Jun. 19, 2012

(54) **CASE FOR A MOBILE COMPUTING DEVICE**

(75) Inventors: **John Van Den Nieuwenhuizen**, San Francisco, CA (US); **Seungheon Lee**, Milpitas, CA (US)

(73) Assignee: **Hewlett-Packard Development Company, L.P.**, Houston, TX (US)

(**) Term: **14 Years**

(21) Appl. No.: **29/385,004**

(22) Filed: **Feb. 7, 2011**

(51) LOC (9) Cl. **14-02**

(52) U.S. Cl. **D14/440**

CLAIM

The ornamental design for a case for a mobile computing device, as shown and described.

DESCRIPTION

FIG. 1 is a front perspective view of a case for a mobile computing device;

FIG. 2 is a front view of a case for a mobile computing device;

FIG. 3 is a back view of a case for a mobile computing device;

FIG. 4 is a bottom end view of a case for a mobile computing device;

FIG. 5 is a top end view of a case for a mobile computing device;

FIG. 6 is a left side view of a case for a mobile computing device; and,

FIG. 7 is a right side view of a case for a mobile computing device.

The broken line portions are not claimed.

1 Claim, 4 Drawing Sheets
